(57) **CLAIM**

The ornamental design for breathing monitor, as shown and described.

DESCRIPTION

FIG. 1 is a perspective view thereof;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a reference view thereof, wherein the breathing monitor of the present design is disposed in a housing;
FIG. 9 is a reference view thereof, wherein the sensor of the breathing monitor is attached to a neck of a user; and,
FIG. 10 is a reference view thereof, wherein the sensor of the breathing monitor is held on a housing with a belt.
The broken lines in the FIGS. 8-10 illustrate unclaimed environment only and form no part of the claimed design.
